UNITED STATES PATENT OFFICE.

JOHN D. WARRELL, OF DEWEYVILLE, TEXAS.

FAN ATTACHMENT FOR SEWING-MACHINES.

1,114,076.

Specification of Letters Patent.

Patented Oct. 20, 1914.

Application filed April 1, 1914. Serial No. 828,856.

To all whom it may concern:

Be it known that I, JOHN D. WARRELL, a citizen of the United States, residing at Deweyville, in the county of Newton and 5 State of Texas, have invented certain new and useful Improvements in Fan Attachments for Sewing-Machines, of which the following is a specification, reference being had to the accompanying drawings.

10 This invention relates to new and useful improvements in fan attachments for sewing machines, the main object of the invention being the provision of a fan which is adapted to be removably applied to the fly 15 wheel of a sewing machine, in order to generate an air draft during the operation of the machine.

Another object of the invention resides in the provision of a fan attachment of the 20 above character which will possess advantages in points of efficiency and durability, is inexpensive to manufacture and, at the same time, is simple in construction and operation.

25 With the above and other objects in view, the invention consists in the novel features of construction, combination and arrangement of parts as will be hereinafter referred to and more particularly pointed out in the 30 specification and claims.

In the accompanying drawing forming a part of this specification, Figure 1 is a front elevation of a fan attachment constructed in accordance with my invention; and Fig. 2 35 is a transverse sectional view taken on the line 2—2, Fig. 1.

Referring more particularly to the drawing, 1 indicates the fly wheel of a sewing machine, upon which my improved fan is 40 adapted to be mounted. The fan attachment includes a circular split band 2 which is substantially arcuate in cross section, so as to conform to the curvature of the periphery of the fly wheel 1. The annular side 45 edges of the band 2 are bent upon themselves to form channels 3, in which the binding rings 4 are mounted. It will be noted that the band 2 contains sufficient resiliency so that when the same is arranged 50 upon the periphery of the wheel 1, it will be readily retained against outward movement until pressure is applied thereto and the retaining wires or rings 4 will securely

hold the band against lateral movement. Formed integral with the band 1 and projecting from the outer side thereof, are the spaced ears 5, to which are secured the fan blades 6, said blades being provided with a reduced portion 7 adapted to be arranged between the ears 5 and riveted or otherwise 60 secured thereto.

From the above it will be readily apparent that my improved fan attachment may be quickly and readily applied to the fly wheel of a sewing machine or removed 65 therefrom. It will also be apparent that after the band is arranged in position upon the fly wheel 1, the wire rings 4 will engage upon opposite sides of the wheel and retain the band against lateral movement, and it 70 will be apparent that the resiliency of the band 2 will be sufficient to clamp the same tightly upon the wheel, said band being formed of galvanized iron or heavy tin. It will also be apparent that the device may 75 be applied to a sewing machine wheel, whereby the air draft therefrom may be projected toward the operator or in the opposite direction. It will also be apparent that the device is extremely simple in construction and can be manufactured and placed 80 upon the market at a comparatively low cost.

While I have shown and described the preferred form of my invention, it will be 85 obvious that various changes in the details of construction and in the proportions may be resorted to for successfully carrying my invention into practice, without sacrificing any of the novel features or departing from 90 the scope of the appended claims.

Having thus described this invention, what I claim is:—

1. A device of the class described including a split band substantially arcuate in 95 cross section, the annular edges of said band being bent upon themselves to form beadings, retaining rings arranged within said beadings, and a plurality of fan blades secured to the outer faces of said band at one 100 side thereof.

2. A device of the class described including a split band, substantially arcuate in cross section and having its annular edges bent upon themselves to form projections, 105 yieldable retaining rings arranged within

said projections, perforated ears formed integral with the band and projecting upwardly from the outer face at one side thereof, and a plurality of fan blades having reduced portions adapted to be secured to said perforated ears, as and for the purpose set forth.

In testimony whereof I hereunto affix my signature in the presence of two witnesses.

JOHN D. WARRELL.

Witnesses:

E. J. SHADDOCK,
J. S. McMAHON.
